UNITED STATES PATENT OFFICE.

LANDON C. MANNING, OF NEW YORK, N. Y., ASSIGNOR TO PACK SHOPS, INC., OF NEW YORK, N. Y., A CORPORATION OF NEW YORK.

VENDING MACHINE.

Application filed November 5, 1925. Serial No. 66,906.

The invention relates in general to a coin controlled, manually actuated vending machine of the type intended for use in vending different articles of manufacture and the invention specifically relates to a replaceable mechanical unit constituting one of a plurality of such units installed in the complete machine, and comprising the coin controlled package ejecting features of such unit.

More definitely classified, the invention relates to the package ejecting features of a standardized unit intended to be assembled in a casing with other similar units to form a composite vending machine capable of storing and discharging articles of different outlines and dimensions, and with the several articles vended solely by the insertion into the associated coin slot of the appropriate dimension of coin intended for that particular unit.

In such forms of vending machine, it is required at present to construct the package handling mechanisms of such size so as to handle some particular size of package and when completed the mechanism of course cannot be used to handle a different size package nor a package intended to sell at a different price. In attempting to maintain an automatic selling service, it is required that the assortment of merchandise appropriated to any one particular machine be changed frequently to meet the current demands for certain groups of articles.

Accordingly the primary object of the invention is to provide a simplified form of multiple article vending machine which will include a plurality of standardized units of vending mechanisms, one for each of the articles vended, and each of which units will be characterized by an adaptability to modify the same easily to accommodate a different size article and to be controlled by a different dimension of unlocking coin.

This phase of the invention is attained by making the parts forming the package reservoir and the coin chute of replaceable elements which can be manufactured in sets of different sizes and carried as replacement parts by the refilling agent in making his rounds.

Should it be desired to discontinue any one article and replace the same by a different size or price article the agent either removes the unit as a whole from the casing and replaces the same or he may simply substitute

for the old reservoir or coin chute, or both, a proper size element to vend the substituted article.

Vending machines of the class under discussion are frequently subjected to rough usage in attempts to cause them to discharge packages illegally and particularly where bulky articles are to be vended there is the necessity of utilizing rugged and massive machine parts to give the requisite strength. In machines intended for vending small packages such as chewing gum, chocolate and the like, the inserted coin was made to form a connecting element of the ejecting mechanism and was therefore required to transmit therethrough strains from the manually actuated handle to the package to be ejected. While this worked satisfactorily where small light articles are to be moved, it was not found practical in handling heavy articles to depend on the coin to transmit the necessary ejecting force.

Accordingly the invention has for another object the providing of a coin controlled ejecting mechanism which can be made as strong as required; which will provide a direct transference of force from the handle to the ejector acting on the vended package through mechanical parts particularly intended and designed for this purpose, and which does not depend on the coin as any part of the strain transmitting mechanism.

This phase of the invention is attained by utilizing the coin simply as a key for shifting a light easily moved latch member into position to connect the handle directly with the ejector mechanism and thus permit the handle to act directly through appropriately designed connecting mechanism and force the ejector on its actuating stroke independent of the subsequent presence of the coin in the mechanism.

Another object of the invention is to provide a form of frame which in addition to its function of supporting the coin controlled ejecting mechanism will be formed in part by replaceable elements designed to be substituted by other similar but different size elements thereby to provide for the vending of different size packages by a standard size of coin control mechanism.

Another object of the invention is to provide a readily replaceable form of coin chute which can be substituted for other dimensioned coin chutes thereby to control the

ejecting mechanisms by coins of various dimensions, whereby, a standard form of ejecting mechanism may be utilized for vending articles at different prices.

- 5 Another difficulty which presents itself when it is attempted to vend heavy, bulky articles from a reservoir stack of such articles, is that any ejecting mechanism after it has functioned to discharge the lowermost package from the stack is retarded, if not entirely prevented, from retreating back to its initial position due to the necessity of moving against the resistance of the entire weight of the packages remaining in the stack, and this is especially true where a pivotally mounted ejector in describing its usual arc of movement must lift the entire bulk of packages.

Accordingly, another object of the invention is to provide a simple form of ejector mechanism which can function on both its actuating stroke and on its return to normal stroke substantially independent of any necessity of lifting the articles remaining in the stack and which therefore can be constructed of light weight as it is not required to transmit any strains except that necessary to eject the single vended package and this can be attained almost without regard to the mass of the merchandise in the reservoir stack.

Another object of the invention is to provide for an easily manipulated adjustment of the discharge passageway so that the apparatus may be readily adjusted to accommodate the standard unit to vend packages of variable heights.

The invention also features a form of platform for accommodating the packages in the stack and which platform may be of a dimension materially less than the area of the supported package. With such a form of limited area platform it is possible to economize in the space necessary to provide sufficient clearance for the discharged package and the all-over dimensions of the unit or multiples of the unit may be confined to a minimum. Here again is featured economy in space disposition.

This phase of the invention is attained in one embodiment of one invention by providing a bottom to the reservoir of less than one half of the width of the package, measured in the direction in which it is to be ejected. The weight of the superposed packages apparently holds the lowermost package on the bottom or ledge until the ejecting mechanism acts positively to move the package from its position clamped between the upper packages and the bottom or ledge.

Various other objects and advantages of the invention will be in part obvious from an inspection of the accompanying drawings and in part will be more fully set forth in the following particular description of one form 65 of device embodying my invention, and the

invention also consists in certain new and novel features of construction and combination of parts hereinafter set forth and claimed.

In the drawings:—

Figure 1 is a view in side elevation looking at the left hand side of the structure and with the parts in their normal, inoperative position;

Figure 2 is a view in rear elevation of the structure shown in Figure 1 looking at the same from the left hand side of the sheet containing Figure 1;

Figure 3 is a view in front elevation looking at the showing in Figure 1 from the right hand side and with the front supporting plate removed;

Figure 4 is a plan view looking down upon the showing in the preceding figures;

Figure 5 is a fragmentary view showing part of the ejector mechanism in side elevation;

Figure 6 is a fragmentary view of part of the coin chute with the cover plate of Figure 1 removed;

Figure 7 is a view in rear end elevation of the form of ejector mechanism taken from the left hand side of Figure 5 and showing the ejector in operative position;

Figure 8 is a similar view of a modified form of ejector and tipping bottom for the package reservoir; and

Figure 9 is a similar view of still another modified form of ejector mechanism.

In the following description and in the claims, parts will be identified by specific names for convenience of expression but they are intended to be as generic in their application to similar parts as the art will permit.

In the drawings there is shown a front plate 10 constituting part of a casing of a multiple article vending machine and which casing formed of said front plates disposed side by side and with their flanged edges contacting encloses a plurality of the units hereinafter described. This casing as a whole is disclosed and claimed in a companion application entitled "Vending machine casing" filed November 27, 1925, Serial No. 71,599. The mechanism herein disclosed constitutes a complete article of manufacture which can be mounted as a readily replaceable unit on any of the separate front plates which coact to form the casing of the complete machine.

The mechanical parts herein disclosed are themselves assembled as a unit and secured to the front sectional plate 10 by screws 11 passed through apertures 12 and accessible from the rear side of the casing. This mechanism unit is mounted in a frame indicated generally by the reference character 13 and includes a rugged, flat main plate 14 extending vertically and projecting rearwardly from the front plate 10. The front edge of the plate 14 is flanged to provide a vertically

disposed flange support 15 for carrying a slot closure 16 hereinafter more fully described. At the lower end of the flange is secured a U-shaped bracket 17 by means of which the plate 5 flange support 15 is secured to the front sectional plate 10.

The upper inner side of the main plate 14 has affixed thereto a pair of apertured blocks 18 and 19 (see Figure 4) for receiving two of 10 a plurality of upstanding rods 20 which coact to form the upper skeleton outline of a package reservoir 21. The other rods are carried by a Z-shaped plate 22 which has a rear flange 23 demountably secured to the rear edge of 15 the main plate 14, by a clamp 24 and an outstanding front flange 25 secured by screws to the front plate 10. A lug 26 projecting laterally from the plate 22 adjacent its front end provides a support for one of the rods 20 which constitute a front receptacle outlining 20 rod. The flat plate 14 and the Z-plate 22 coact to form the lower portion of the reservoir and define the size and configuration of the horizontal cross sectional area of the complete 25 reservoir. It is understood that the top of the rods 20 are secured in place to complete the reservoir by means more fully disclosed in the companion application above identified. From this construction it is appreciated that it is possible simply by substituting for the plate 22 another size plate with differently located apertures for the rods 20 a different size of reservoir may be provided. This substitution is facilitated by the 30 use of a readily manipulated and removable form of clamp 24 for the rear end of the replaceable receptacle forming plate 22.

For the purpose of giving strength to the Z-plate 22, permit the use of a thin gage metal 40 and at the same time to provide rugged sockets for receiving the lower ends of the rods 20, flat bracing plates 27 are secured, preferably by welding or abrasion, to the sides of the plate 22.

Demountably positioned on the side of the main plate 14 is a unit complete per se and constituting a coin chute and coin ejector mechanism, indicated generally by the reference character 28. The coin chute element is 45 formed of two parallel plates 29 and 30 held in spaced apart position by edge strips 31 more particularly shown in Figure 6. The front plate 29 is secured to the unit formed by the rear plate 30 and by the edge strips 31 by screws 32 passed therethrough and extending 50 into the main plate 14 (see Figure 1). Referring particularly to Figure 6 it will be noted the edge strips and a centrally disposed strip forming a partition 33 form a Z-shaped coin 55 passageway. This passageway includes a slightly inclined incoming coin channel 34 open at its upper, receiving end to a vertically extending coin slot 35 in the front plate 10. The coin receiving portion 34 of the coin slot 60 is L-shaped and at its lower end is outlined

on one side by horse-shoe form of permanent magnet 35 which fills a cut-out opening 37 in the side of the front plate 29. The magnet is secured in place by a screw 38 passed through the coin chute 28 and into the main 70 plate 14. The open space between the legs of the magnet is filled with a finger of non-magnetic material which may be in the form of a finger 39 formed by parallel slits in the side 75 38 and bent therefrom so as to close completely the opening 37. The magnet is positioned above the rear coin passageway 40 which constitutes one of a pair of vertically extending passageways formed by the partition 33; the other forwardly disposed passageway 41 being hereinafter referred to as a slug chute. The passageways 40 and 41 are opened at the bottom of the coin chute through a slug discharging port 42 arranged to coact with ports not herein shown to discharge slugs S from the machine back to the operator through the package discharging opening usual in such constructions, and one form of which is disclosed in the above identified co-pending application. 80

One of the edge strips 43 at the bottom of a rearwardly extending discharge port 44 of the coin chute has a slightly rounded corner providing a coin supporting seat or stop 45 adapted to receive a coin C shown in dotted 90 lines in Figure 1 as it falls down the passageway 40, and into position in the path of movement of a coin ejector 46 hereinafter more fully disclosed. The ejector acts during the initial part of its operation to lift the coin off the seat and start the same rolling down the incline 47 provided by the upper edge of the spacing strip 43. From the upper edge 47 95 the coin is discharged through the port 44 into a coin receptacle (not shown). 100

The coin ejector 46 is at the end of a circumferentially extending flange or finger 47 forming part of a manually actuated coin control wheel 48 pivotally mounted on a pin 49 extending through a hub 50 forming part of the 105 wheel. The wheel and associated parts are readily demountable with the front coin plate 29. The wheel is also provided at its upper portion with a slug ejector 51 extending clockwise from a rearwardly extending arm 52 of the wheel and disposed, when the wheel is rotated clockwise, to engage any slug S which may be held by the magnet 36. (See Figure 6.) The slug ejector acts to move the slug away from the magnet forwardly and permits the same to fall through the passageway 41 and opening 42 to be returned to the operator as previously suggested and as shown in the succeeding dotted line positions of the slug in Figure 6. 110

The wheel and with it its coin and slug ejectors is normally held in its inoperative position to receive the coin or slugs by a long spring 53, the lower end of which is secured by means of a pin 54 to the outside of the 115 120 125

wheel and the upper end is secured in fixed position by means of a pin 55 projecting laterally from the upper end of the main plate 14. The wheel is provided with a forwardly extending plate which projects through a lever slot 57 in the front plate 10 and terminates in a ball 58 constituting a manually actuated handle.

It is desirable in devices of this character when the actuating handle has been started on its actuating movement that the stroke be completed before the actuating mechanism is permitted to return to its initial position. For this purpose there is mounted on the outer

side of the wheel 48 a two-sided double ratchet bar 59 extending concentrically of the axis of rotation of the wheel. The teeth on opposite sides of this bar are disposed in opposite directions with the teeth 60 forming the upper or outer rack having their square shoulder portions facing upwardly and the teeth forming the lower or inner rack 61 having their shoulder portions facing downwardly. Both sets of ratchet teeth are designed to be engaged by a ratchet pin 62 constituting a pawl carried at the upper end of a pawl lever 63 fixed to a shaft 64 pivotally mounted in a sleeve 65 carried by and projecting laterally from the main plate 14.

The pin 62 is normally held in position in a line centered between the two toothed rack surfaces 59 and 60 as shown in Figure 1. This is attained by means of a long, flat spring 66 (see Figure 5) which has its lower end set into and extending diametrically through the shaft 64 and with its upper end extending between a pair of stop pins 67 and 68. In this way the pawl pin 62 is held by the spring 66 in operative engagement with every one of the racks which it may be facing whenever the wheel is moved from its normal inoperative position.

From this construction it will be understood that when the rack bar 59 is in its elevated position as shown in Figure 1 the rack as a whole will be positioned above the pin 62. As the handle 58 is lowered the rack is carried downwardly with the pin riding idly on the teeth forming the upper rack 60 but should an attempt be made to cause a retreat upwardly of the wheel, the pin would be engaged by the upwardly facing shoulders and any further movement would be prevented by the engagement of the shoulders of the teeth with the ratchet pin 62. When the ratchet bar 59 has reached the end of its lowered movement the pawl pin 62 will be swung by the spring 66 over the top of the upper pointed end of the bar and while the wheel is being returned under tension of the spring 53 such movement cannot be intercepted by an attempt to move handle 58 downwardly due to the engagement of the ratchet pin 52 with the shoulders upwardly facing on the upper side of the rack.

Positioned in the path of the coin C as it is lifted from its seat 45 by the ejector 46 is the reduced end 69 of a latch lever 70, which end projects laterally through an aperture 71 (see Figures 1 and 6) formed in the coin chute. The lever constitutes a control for setting the package ejecting mechanism and is pivotally mounted midway of its ends on a pivot pin 72, pivotally mounted on a swinging plate 73 forming part of a frame 75 constituting a package ejector 74. The package ejector is rotatably mounted upon a shaft 75 mounted in the frame of the machine directly below the package receptacle. The package ejector is normally held with its upper end in engagement with the main plate 14 by means of a spring 76 coiled about one of the spacing sleeves 77 on the shaft 75 with one end of a spring underlapping the plate 14 and the other end 78 of the spring bearing on the rear side of the plate 73. A relatively weak spring 79 between the lever 70 and the plate 73 acts normally on the lever to position the end 69 thereof in the path of movement of the upper edge of the coin and to raise the opposite end 79. Normally this opposite end will be thus raised out of the path of movement of a hook-shaped lever 80, hereinafter referred to as a power member rotatably mounted on the shaft 75. The lever 80 is swung on its arc of movement normally past the end 79 but into engagement with this end 79 when the same has been lowered by the presence of the coin lifting the end 69. The lever 80 is at all times connected to the manually actuated wheel. This is attained through the agency of a link rod 81, the upper end of which is pivotally connected by means of a pin 82 carried by an outstanding finger 83 projecting laterally from an arc-shaped flange 84 forming part of the wheel 48. This flange 84 constitutes a curved closure disposed concentric of the axis of the wheel for covering the slot in the plate 10 through which the handle plate 56 projects. The lower end of the rod is pivotally connected by means of a pin 85 with a lever arm 86 projecting from the shaft 75. Preferably the connection between the lever 86 and the shaft is made adjustable and for this purpose the lever is provided at its lower end with a slot 87 enlarged at its lower end (shown in Figure 3) to provide a bifurcated end straddling the shaft 75. The lever 86 is secured in its longitudinally adjusted position relative to the shaft by means of a jam nut 88 screwed into a segment plate 89 secured to the shaft 75.

To limit the movement of the power lever 80 into its normal inoperative position (shown in Figure 3) an L-shaped stop 90 is rotatably mounted on the shaft 75 and is secured to the segment plate 89 by means of a pair of set screws 91 and 92. The flange portion 93 of the stop 90 overlaps the edge of a plate 94 constituting an upturned flange of

the ejector plate 73 to limit the retreat of the power lever under action of the spring 53.

Referring to the form of ejector shown in Figures 5 and 7, the upper edge of the plate 73 is provided with a laterally extending flange 95 designed to swing therewith about the axis of the shaft 75 and past the three fixed feet 96, 97 and 98 constituting the bottom of the package reservoir 21. These feet form in effect a single flat ledge horizontally disposed and designed to support the packages in the reservoir. These feet are spaced apart to permit the movement therewith of a pair of ejector arms 99 and 100 swinging about the shaft 75 as a center. The arms are each made up of a pair of parallel plates 101 and 102 with their lower ends bifurcated as shown at 103 in Figure 7 and with their upper ends connected by a roller 104 mounted on a connecting pin 105 and constituting the element designed to engage the package to be vended as shown in Figure 7. The ejector arms 99 and 100 are supported by means of a rocking shaft 106 suspended at opposite ends from hanging arms 107 and 108, the upper ends of which are pivotally connected by means of pins 109 to depending flanges 110 forming part of the end feet 96 and 98. The hanging arms 107 and 108 are so proportioned that when the ejecting mechanism is operated the rollers 104 will not describe an arc of movement concentric of the axis 75 as is usual in such constructions, but will move horizontally in its package ejecting movement as indicated in Figure 7 and will eject the lowermost package from the stack of packages moving in a substantially straight line beneath the next adjacent lowermost package. It is a feature of this disclosure that the rollers in ejecting a package from the stack have a straight linear movement across the top of the supports forming the bottom of the receptacle and do not raise above the bottom. In this way the ejecting mechanism is not required to lift the mass of unvended packages in the stack.

While the form of ejecting mechanism thus described in connection with Figures 5 and 7 works with entire satisfaction especially in connection with small and light weight packages, it is noted from the showing in Figure 7 that the entire weight of the superposed packages remaining in the reservoir is pressing on the roller 104. This tends to prevent the retreat of the ejecting mechanism, and if the packages in the reservoir happen to be heavy, a powerful spring 76 would have to be used to overcome the resulting frictional resistance to the retreating movement of the rollers after it has functioned to eject the preceding package. Even then a forceful retreat of the part of the ejecting mechanism engaging the packages is very apt to injure the goods or its wrapper.

Accordingly, there is suggested in the mod-

ified form shown in Figure 8 an arrangement of tipping bottom for the reservoir designed to provide for a movement of the ejecting mechanism of less extent than is necessary with the form shown in Figure 7, and in which the discharging end of the support is arranged to tip down and thus permit the partially ejected package to drop out rather than be pushed entirely out of the stack. For this purpose the ledges forming the bottom of the reservoir and corresponding to the feet 96, 97 and 98, are each formed of two parts, an inner fixed L-plate 110 to the outer edge of which is pivoted, by means of depending lug 111, an outer drop plate 112 to form a tipping platform defining the discharge end of the chute bottom. The three sets of the two plates 110 and 112 coact normally to form a fixed horizontal support for the stack of packages in the reservoir as shown in Figure 8. The plate 112 is connected by means of a rod 113 with an arm 114 forming an extension from the hook-shaped lever 80 so that in the form shown in Figure 8, the lever 80 constitutes a bell-crank lever supported on the shaft 75. From this construction it is seen that as the lever 80 is actuated to cause the ejecting mechanism to function it will towards the end of its ejecting action cause the outer portion of the stack support to tip as indicated by the arrow at the right of Figure 8.

In this modification there is also shown a slightly modified form of package engaging element differing from the rollers 104 in that the part used for engaging the package is in the form of an S-shaped pusher plate 115 pivoted on a pin 116 connecting the arms 101 and 102 and which pin takes the place of the roller carrying pin 105.

In the modified showing in Figure 8 the feet 96, 97 and 98 are connected to form the horizontal ledge 117 as a single plate from the underside of which the hangers 107 may be suspended. The rear part of this ledge 117 is broken away to provide a recess opening 118 for receiving the pusher 115 as it is returned in its normal inoperative position shown in Figure 8. The pusher includes a short upstanding lip 119 having a length 115 from its axis of rotation so as to extend a short distance below the top of the lowermost package in the stack. The other arm 120 being longer than the lip 119 normally depends from the pivot pin 116 and is somewhat 120 U-shaped to form a spacer about the depth of the thickness of the package being vended. The end of this arm 120 is disposed so that it engages the side of the main plate 14 as shown in Figure 8 and thus causes the lip 119 to stand vertically in the rear of the stack of packages when in its rearmost position. During the ejecting operation the arm 120 is tripped by its engagement with the forward edge of the recess 118 and the arm 120 is held in position 130

elevated above the support 117 and in this way the remaining packages in the stack are held in their previous elevated position while the lowermost package is being ejected and 5 until the ejecting mechanism has retreated to its initial position clear of the stack.

The slot closure 16 includes a long upstanding lever 121, pivotally mounted on pin 122 with its upper end provided with a flange 123 10 for covering the coin slot 35 in the plate 10. The lever is held normally in inoperative position uncovering the port by means of a coiled spring 124 and a stop 125 limits the movement of the lever under the tension of 15 this spring. The lever 121 is also provided with an off-standing finger 126 which is designed to be engaged by a pin 127 projecting from one side of a weight 128 resting on top of the stack of packages in the reservoir and 20 designed so that when the reservoir is emptied of its packages the pin will engage the finger and shift the lever into position closing the coin slot. The lower end of the lever 121 is provided with an offset extension 129 disposed 25 in the path of movement of the curved face plate 84 forming part of the manually actuated control wheel 48 so that at each actuation of the handle 58 the coin slot is automatically closed.

The opening in the lower end of one side of the package reservoir is made adjustable so as to accommodate the same to the vertical depth of the variable size packages which the machine is to vend. For this purpose a plate 30 130 is disposed so that its lower edge 131 defines the upper edge of the opening. The plate is secured in its adjusted position by means of set screws 132.

In the showing in Figure 9 the bottom support for the packages in the reservoir is provided by a horizontal ledge 117 having a width in the direction of movement of the package while being ejected of about one half, or less, the corresponding width of the package. It is appreciated that the weight of the packages superposed on the lowermost package acts to hold the lowermost package from tipping off the ledge.

In this instance the package engaging element differs from both the rollers 104 and the pusher plate 115 in that it is a normally upstanding weighted plate 133 pivoted on pins 134 to the upper edge of the plate 73. The axis of rotation provided by the pins 134 is positioned to swing below the ledge 117. From this construction it is apparent that on its ejecting stroke the upper edge 135 of the pusher plate 133 acts to push the lowermost package laterally in the direction of 55 its unsupported part and unbalance the same so that the package freely escapes from the stack. On the return stroke the plate is free to swing on its axis so that the upper edge 135 scrapes along the underside of the next lowermost package until 60

it clears this package when it is free to swing by virtue of its lower weighted end 136 into vertical position back of the stack. If, for any reason, it should tend to stick in its canted position the movement thereof into engagement with the support would cause it to assume its normal position in position to eject the next package.

Having thus described my invention, I claim:

1. In a vending machine, the combination of a plurality of similar units coacting to provide a multiple article vending machine, each unit including a front plate constituting a part of the casing of the complete machine 80 and outlined at opposite vertical edges with inturned flanges adapted to contact with the similar flanges of the front plates of the next adjacent unit or units, a mechanical unit mounted at the rear side of the front plate, 85 screws accessible from the rear side of the front plate for demountably securing the unit to the front plate, said unit including a package ejecting mechanism.

2. In a vending machine, a mechanism containing frame including a vertically disposed main plate provided with means at its front end for mounting the same to a support, a package ejecting mechanism carried by the main plate, a Z-plate coacting with the main plate to form the lower portion of a package containing reservoir, reservoir forming rods carried by the main plate and Z-plate and a clamp for securing the plate.

3. In a vending machine, a mechanism containing a frame including a vertically disposed main plate provided with means at its front end for mounting the same to a support, a package ejecting mechanism carried by the main plate, a Z-plate coacting with the main plate to form the lower portion of a package containing reservoir, and rods carried by the Z-plate and coacting with the main plate to provide the upper portion of said reservoir.

4. In a vending machine, the combination of a package support constituting a flat ledge adapted to constitute the bottom of a package reservoir, and an ejecting mechanism including an upwardly extending rocking arm positioned beneath the ledge and having its upper end extending at all times above the support, a package engaging member pivoted to said projecting upper end, supported on the ledge and guided thereon to have a straight linear movement across the top of the flat support.

5. In a vending machine, the combination of a package support constituting a flat ledge adapted to constitute the bottom of a package reservoir, an ejecting mechanism including a hanger pivoted at its upper end to the support, rocking arms supported by the hanger and projecting above the support, and a package ejector pivoted to the upper 125 130 135

ends of the arms and at all times having a straight linear movement across the top of the flat support, and pivotally mounted means acting on the linearly moving ejector for actuating the same.

5. In a vending machine, the combination of means forming a vertically disposed package containing reservoir, a horizontal support forming the bottom thereof, an ejector mounted to move straight across said support to eject the lowermost package in the reservoir and provided with a smooth side for permitting the retreat of the ejector to its initial position without damage to and without lifting the remaining packages in the reservoir.

6. In a vending machine, the combination of a support for the package to be vended, a swinging ejector mechanism, means for swinging said mechanism as a whole about an axis of rotation, said ejector having a limited freedom of longitudinal movement relative to said axis of rotation, said mechanism including a package engaging element, a pivotal connection between said element and the ejector, and means for confining the movement of said pivotal connection to a straight line above and parallel to the support when the ejector mechanism is swung into operative position about its axis.

7. In a vending machine, the combination of a shaft, an ejecting mechanism including a plate rockably mounted on the shaft and having a limited movement longitudinally relative to said shaft, means for swinging the plate, an ejector arm carried by the plate free to move relative thereto and provided with means for engaging the package to be vended, and means for causing said package engaging means to move in a straight line as the plate is rocked about the axis of the shaft.

8. In a vending machine, the combination of a plate mounted for swinging movement about an axis of rotation, an ejecting arm slidably guided for reciprocatory longitudinal movement on said plate, a lip pivoted to one end of the arm, and linkage operatively connected to the arm to cause the same to move bodily along the straight line as the plate is rocked about said axis.

9. In a vending machine, the combination of a plate mounted for swinging movement about an axis of rotation, hangers for supporting said plate, an ejecting arm mounted on said plate and free to move longitudinally relative thereto, a pivoted lip carried by one end of the arm, linkage operatively connected to the arm to cause the lip to move bodily along a straight line as the plate is rocked about said axis, and a spring acting on the plate to return the same and the lip to a normal inoperative position when free of restraint.

10. In a vending machine, the combination of means forming a package reservoir, a bottom therefor comprising a fixed support and a tipping platform pivoted to one side edge thereof, and ejecting mechanism for shifting the lowermost package from the bottom towards the tipping platform.

70

11. In a vending machine, means forming a package reservoir, a bottom therefor comprising a fixed support and a tipping platform pivoted to one side thereof, ejecting mechanism for shifting the lowermost package from the bottom towards the tipping platform, and connecting means between the ejecting mechanism and the platform to cause the same to tilt incidental to the ejection of the package from the bottom.

75

12. In a vending machine, the combination of a fixed package reservoir, a normally fixed support for the packages in said reservoir, and manually actuated means for simultaneously pushing the lowermost package out of said support and for causing said support to tilt and thus assist in removing said package.

80

13. In a vending machine, the combination of a fixed package reservoir, a normally fixed support for the packages in said reservoir, and manually actuated means for simultaneously pushing the lowermost package out of

85

14. In a package vending machine, a package supporting means including a fixed ledge and a pivotally mounted drop plate, a package pushing device for shifting a package off the fixed ledge towards the drop plate and means connected with said pushing device for controlling the drop plate.

90

15. In a vending machine, the combination of a package support, a pivotally mounted S-shaped package pusher at all times positioned above the top of the package support and disposed in its movement in one direction for shifting the package off said support, means

95

160

16. In a vending machine, the combination of means forming a package reservoir, means forming a bottom for the same and including a tilting package discharging port, ejecting means for discharging from the bottom the lowermost package of the stack and for preventing the falling on to the bottom of the next succeeding package of the stack and manually actuated means operatively connected to both the ejecting means and to the

125

18. In a vending machine, the combination of means forming a package reservoir, means forming a bottom for the same and including a tilting package discharging port, ejecting means for discharging from the bottom the lowermost package of the stack and for preventing the falling on to the bottom of the next succeeding package of the stack, manually actuated means operatively connected to both the ejecting means and to the tilting part of the bottom to cause the same to function in unison, and means acting on the ejector and tilting bottom to restore the same to their

130

normal positions when free of the restraint from the manually actuated means.

18. In a vending machine, the combination of means forming a package reservoir including a bottom plate, a shaft, an ejecting mechanism including a pair of arms having bifurcated ends straddling said shaft, a pusher pivotally mounted between the arms, means for suspending the arms and manually actuated mechanism operatively connected to said ejecting mechanism to cause the pusher to move in a straight line along the top of said bottom plate.

19. In a vending machine, the combination of means forming a package reservoir including a bottom forming member, reciprocating means movable back and forth across the top of said bottom member in one direction to eject the lowermost package in the reservoir and in the other direction to retreat into its normal inoperative position, said means including pivotally mounted package ejecting pusher plate sliding on the bottom member and disposed during its package ejecting movement to prevent the premature falling of the next package on to the bottom member prior to the retreat of the ejecting means.

20. In a vending machine, the combination of means forming a package reservoir including a bottom forming member, reciprocating means removable back and forth across the top of said bottom member in one direction to eject the lowermost package in the reservoir and in the other direction to retreat into its normal inoperative position, said means including a pivotally mounted S-shaped pusher plate, sliding along the top of said bottom during its package ejecting movement and acting to prevent the premature falling of the next package on to the bottom member prior to the retreat of the ejecting means, and means controlled by the return to normal of said ejecting means for permitting the next succeeding package to fall into position on the bottom member in advance of the ejecting means.

21. In a vending machine, the combination of means forming the bottom of a package reservoir, ejecting mechanism including a swinging frame, said frame including an S-shaped pusher pivotally mounted intermediate its ends and moved on the actuation of the ejecting mechanism across the top of the bottom to eject the package in the bottom, and means controlled by the position of the ejecting mechanism relative to the bottom for tripping the S-pushers into and out of its operative position.

22. In a vending machine, the combination of means forming the bottom of a package reservoir, ejecting mechanism including a swinging frame, said frame including an S-shaped pusher pivotally mounted and moved on the actuation of the ejecting mechanism across the top of the bottom to eject

the package in the bottom, said pusher including a normally upstanding relatively short lip for engaging the package to be ejected and also including a somewhat U-shaped spacer for supporting spaced above the bottom the stack of packages above the package being vended.

23. In a vending machine, the combination of a package receptacle provided with a discharge opening, ejecting mechanism for discharging packages from the receptacle horizontally through said opening, and adjustable means for varying the size of said opening.

24. In a vending machine, the combination of a package receptacle provided with a discharge opening, ejecting mechanism for discharging packages from the receptacle horizontally through said opening, a plate having a lower edge defining the upper edge of said opening, and means for securing the plate in adjusted position.

25. In a vending machine, means forming a package reservoir, said reservoir having a bottom forming member providing a support of less area than the cross sectional area of the reservoir whereby the lowermost package in the reservoir is only partly supported and with one edge part unsupported and ejecting mechanism for moving the lowermost package in the direction of its unsupported part.

26. In a vending machine, the combination of means forming a reservoir for a stack of packages to be vended, one side of the reservoir being open to provide a discharge outlet, a fixed horizontal support for said stack of packages, said support having a package discharging edge terminating in spaced relation to the outlet whereby the portion of the lowermost package nearest the outlet is unsupported and ejecting mechanism for moving the lowermost package from the stack towards said outlet and off said fixed discharging edge.

27. In a vending machine, package ejecting mechanism including a swinging member, mounted for reciprocatory rocking movement, manually actuated means for swinging said member on its actuating stroke, and a package engaging member pivotally mounted on the swinging member, a stop, said package engaging member provided with means movable into engagement with the stop on the retreat of said swinging member for setting the package engaging member into a vertical position in rear of the next package to be vended.

28. In a vending machine, package ejecting mechanism including a swinging member, mounted for reciprocatory rocking movement, manually actuated means for swinging said member on its actuating stroke, a package edge engaging member pivotally mounted on the swinging member for

movement about a horizontal axis, said member being mounted to cause the upper portion to stand vertically when in operative position at one side of and engaging a vertical edge of the package being ejected and adapted to be swung into position to clear the packages in the stack when returning on its inoperative stroke.

29. In a package vending machine, the combination of a horizontal support for packages to be vended, manually actuated ejecting mechanism including a swinging plate, and a normally vertically disposed package engaging member pivoted to said plate for swinging movement about an axis at all times disposed above the support.

30. In a package vending machine, the combination of a horizontal support for packages to be vended, manually actuated ejecting mechanism including a swinging plate, 20 a normally vertically disposed package engaging member pivoted to said plate for swinging movement about an axis at all times disposed above the support, and said weighted member having an upper portion extending above the support for a distance less than the depth of the package to be vended.

Signed at New York, in the county of New York and State of New York, this 21st day of Oct., A. D. 1925.

LANDON C. MANNING.
